WELL PUMPING APPARATUS

Clarence N. Scott, Houston, Tex.

Application June 1, 1937, Serial No. 145,693

6 Claims. (Cl. 103—52)

My invention relates to the operation of bored wells equipped with pumping apparatus for raising the fluid from the pumping depth in the well to the surface of the ground.

5 The fluid is caused to flow from the producing formation into the lower part of the well bore or cavity by removing from the well the liquid and gas by natural or artificial means, thus reducing pressure in, or removing it almost entirely from, 10 the well bore or cavity and the adjacent producing formation. This enables superior fluid pressure in the outlying producing formation to move the fluid towards and into the well unimpeded by bottom-hole pressure or back pressure in the 15 same.

Other things being equal the production of fluid of a well will vary between zero when bottom-hole pressure in the same is at its maximum and equals stabilized formation pressure; and 20 maximum production of fluid when bottom-hole pressure is entirely removed. It follows then that when the maximum production of fluid is desired, or protection or advantage against offset wells is required or desired, bottom-hole pressure 25 should be reduced to the minimum. This minimum in practical operation is largely dependent upon and varies with the character of and method of installing the pumping apparatus used.

My invention has particular relation to that 30 class of pumping apparatus known as plunger-lifts in which the liquid is lifted to the surface from the pumping depth in the well, riding on top of a free plunger traveling in a smooth bore eduction tube. This is accomplished without dis- 35 charging any portion of the slug of liquid so riding, nor reducing its volume during the major part of its up-stroke until the upper end of the liquid slug reaches the discharge opening of the eduction tube. The discharge of the liquid by 40 the plunger is then begun and thereafter continued until the plunger reaches the end of its stroke. The plunger is propelled by gas in the eduction tube under the same. Said gas may be produced currently from the producing forma- 45 tion with the oil, or from an independent surface source of supply, or by the former if inadequate supplemented by the latter.

In such plunger-lift devices installed in even 50 only moderately deep wells the time consumed in a plunger round trip is considerable and consequently the number of such round trips per unit of time is so reduced that the slug of liquid required to be handled per round trip of the plunger is of considerable height and its static 55

pressure and accordingly the required plunger-propelling gas pressure are correspondingly great. Under favorable conditions with such plunger-lift apparatus the plunger propelling gas pressure which must be maintained in the well casing outside of the eduction tube above the operating liquid level in the well is from 25% to 50% greater than the static pressure of the column of liquid riding on top of the plunger. To this increased pressure must be added, to 10 determine full bottom-hole pressure, the static pressure of the column of liquid from the operating liquid level in the well outside of the eduction tube to the bottom of the hole. This bottom-hole pressure is continuous and without material 15 variation in pressure during the operation of the plunger-lift. This excessive bottom-hole pressure exerts a correspondingly high back pressure against the fluid in the producing formation adjacent the well bore and reduces to this material extent the moving effect of the fluid pressure in the outlying producing formation. This 20 accordingly reduces materially and seriously affects the production of fluid of the well.

It is an object of my invention to provide a 25 well-pumping apparatus which will retain all the advantages of the regular single stage plunger-lift device and at the same time utilize to a material degree the lifting power of the formation gas currently produced from the pro- 30 ducing formation with the liquid to be removed from the well, without subjecting the well bore and the adjacent producing formation to ob- 35 jectionably high bottom-hole pressure, but with propelling gas so low in pressure as to render negligible the resulting back pressure acting against the fluid flowing into the well bore.

It is also an object of my invention to provide a method of and apparatus for operating wells 40 which will combine low lifting cost with the highest potential production of the fluid sought.

It is another object to provide a well pumping apparatus and method for and of operating wells which by reason of its flexibility can by simple 45 adjustment on the ground be readily adapted to meet any conditions of well, formation and fluid.

It is a further object to provide a fluid-removing apparatus which will be automatic in the complete performance of its regular operating functions or cycles and require a minimum of 50 operating attention.

It is a further object to provide a fluid-removing apparatus which while removing the liquid from the pumping depth in the well will also remove and/or effect the escape or release of 55

formation gas currently produced from the producing formation with the said liquid, even though this gas be largely in excess in quantity over that which can be advantageously utilized in raising the liquid and in effecting gas escape through the eduction tubes following release of the plunger-propelling gas from said tubes.

It is an object of major importance to provide a fluid-removing apparatus which while removing the liquid and formation gas from the well will reduce bottom-hole pressure in the well to a practical operating minimum favorably comparable with that effected by the most efficient of other such devices.

15 I have illustrated the invention as applied to a pumping well equipped with my device for raising the oil and gas from the pumping depth to the surface of the ground.

16 In the drawings herewith:

20 Fig. 1 is a central longitudinal section through the extreme upper portion of a well installation embodying my invention. This entire portion is above ground. More correctly speaking this is the extreme upper portion of the upper or secondary lift.

25 Fig. 2 is a similar section through an intermediate portion of the same well installation. It shows the extreme lower portion of the secondary lift. It adjoins that shown by Fig. 3 on the line A—B.

30 Fig. 3 is a similar section through another intermediate portion of the same well installation. It shows the extreme upper portion of the lower or primary lift. It adjoins that shown by Fig. 2 on the line A—B.

35 Fig. 4 is a similar section through the extreme lower portion of the same well installation, which is also the extreme lower portion of the primary lift.

40 Fig. 5 shows an alternative arrangement in which the string of tubing which extends from the gas admission valve housing to the top of the well and which forms and separates the pressure gas passageway from the casing space, is omitted and a packer is installed above the said housing to partition the casing space into upper and lower compartments. In this arrangement, pressure gas from the surface source would be conveyed to the gas admission valve housing by the upper casing 45 compartment and the low well pressure above the liquid in the well bore or cavity would be in the lower compartment below the packer. A separate gas pipe may be strung from the packer through the upper casing compartment to make 50 communication between the surface and the lower casing compartment, if desired.

55 Fig. 6 is a fragmentary section on a larger scale through a part of the lower portion of the secondary lift shown by Fig. 2. It shows in greater detail of construction the gas admission valve which admits pressure gas procured from a surface source to the annular liquid-receiving, storing and transferring chamber after said chamber has been charged with liquid discharged 60 into it by the several consecutive strokes or cycles of the primary lift plunger.

65 Like parts shown in the several figures have the same reference numbers.

The well casing 1 usually extends from the top 70 of the well to a point above the producing formation where it is cemented. 2 is the primary smooth bore eduction tube and extends within the casing from near the bottom of the well bore to a primary lift discharge chamber 18. This 75 chamber and the liquid-receiving, storing and

transferring chamber are located at as great a predetermined elevation or height in the well as will permit of the most advantageous utilization for liquid lifting purposes, of the maximum quantity of formation gas available and currently produced. The lift must be done without reducing the number of round trips of the primary lift plunger per unit of time to such a degree as to excessively increase the height of the slug of liquid carried on the primary plunger per trip 10 and consequently the plunger propelling gas pressure in the casing with the resulting excessive bottom-hole pressure. In other words, in practice the height or elevation of the top of the primary eduction tube should be a compromise between the degree or extent of the utilization of formation gas for liquid lifting and the maintenance of the reasonable minimum bottom-hole pressure. 3 is the secondary smooth bore eduction tube and extends upwardly from the primary discharge chamber 18, at an elevation slightly above the upper end of the primary eduction tube, to the top of the well above ground. The diameter of this secondary eduction tube should preferably be larger than that of the primary eduction tube to facilitate the withdrawal of the discharge valve and valve seat and the plunger of the primary lift without removing the secondary eduction tube from the well. Or its diameter may be still further increased over that of the primary eduction tube when it is desired to increase fluid lifting capacity without increasing the diameter of the primary eduction tube because of well bore or casing diameter limitations at the lower end of the well.

4 is a string of tubing extending from the gas admission valve housing 8 to the top of the well. It forms between its inside diameter and the perimeter of the secondary eduction tube 3 an annular passage 5 through which pressure gas 40 from a surface source of supply is conveyed to the gas admission valve, from and by which it is delivered to the chamber 7 to displace and raise the liquid from same into the primary lift discharge chamber 18 and secondary eduction tube 3 to load and propel the secondary plunger 25. The tube 4 also forms, between its perimeter and the inside diameter of the casing 1, an annular passage 6 through which formation gas in excess of that which passes through the eduction tubes 2 and 3 to the surface may escape to the surface, or through which a supply of pressure gas from a surface source may be conveyed to the well bore or cavity 12 above the liquid level in same for liquid lifting purposes in the primary lift when formation gas is of insufficient quantity.

The space 7, as seen in Fig. 3, is a double legged U shaped liquid-receiving, storing and transferring chamber formed by the tubular members 8 and 9 and the perimeter of the primary eduction tube 2 and the bottom coupling 10. The inner and outer legs 7 are connected together just above coupling 10 by perforations 11 in the lower end of member 9. This chamber 7 is located so that the major portion of its volumetric capacity lies at an elevation in the well below the elevation of the primary lift discharge chamber 18, in order that pressure in chamber 18 opposing the discharge of liquid and gas from the primary eduction tube 2 will not be materially affected or varied by the several subsequent discharges of the primary plunger until chamber 7 is fully charged. Liquid then builds-up in discharge chamber 18 and in secondary eduction tube 3 to the limit of the ability of the primary lift to build 75

it up further and until said built-up column in 18 and 3 has reached the predetermined height sufficient to actuate the opening of gas admission valve 31. Opening valve 31 admits pressure gas from the surface source of supply, to displace and raise the liquid from chamber 7 up into the secondary eduction tube 3 to the loading elevation of the secondary plunger and to propel the said plunger with its superimposed slug of liquid to the top of the well. Between the perimeter of 8 and the inside diameter of casing 1 is clearance space, forming an annular passageway connecting the upper casing space or passage 6 with the lower casing space 12.

5 The primary lift plunger 15 travels in the primary eduction tube 2 from the pumping depth in the well to a point near the upper end of said tube. A cushion stop 13 is provided at the lower end of its travel. Against this stop the stem of the valve 0 14 in the plunger will contact to close the valve. At the upper end of its stroke the plunger discharges its superposed slug of liquid through a primary discharge valve seat 16 and upwardly opening valve 17 to primary discharge chamber 18. Here the liquid spills over and down into the inner leg of chamber 7 at the level 19. From here it flows into the outer leg of chamber 7 through perforations 11. Gas above the plunger passes on up through the secondary eduction tube 3 and out at the surface. The valve seat 17 is shown as screwed into the upper end of the eduction tube. Other means of attachment may be used.

10 The valve 14 in the plunger is opened near the upward limit of its travel by contact with the plunger stop 20. This allows the propelling gas below the plunger and some of the gas from the well bore to escape upwardly to the surface through tube 2, valve 17, chamber 18, tube 3, openings 21 and flow line 22.

15 The secondary stage of my device receives the fluid from the primary stage. The secondary lift plunger 25 has a valve 26, like the valve 14 of the primary plunger. Both plungers, 14 and 25, are of the usual construction now in use. A cushion stop 27 for plunger 25 is formed upon the supporting post 28 mounted on the upper end of valve seat 16. This stop engages the plunger valve 26 and closes it as the plunger approaches its lowest or loaded position. Projections 29 on the upper and lower surfaces of the valve 17 are provided. Those on the lower surface engage torsionally with the ribs in the seat 16. Those on the upper surface engage with fingers, straddling the cushion stop 27, of a setting tool which may be used to screw the valve seat 16 into position in the upper end of eduction tube 2, or to unscrew and withdraw said valve, seat and the primary plunger 15 from the well, without removing the secondary eduction tube 3. 30 is an annular cushioning space formed by a part of the valve seat 16 and the interior surface of the eduction tube 2. The upper end of the plunger 15 as it approaches the upper end of its stroke enters this cushioning space and the gradual release of fluid from the same brings the plunger to rest gradually without harmful impact.

20 31 is an automatic gas admission valve of the annular sleeve valve type. It moves in an annular housing formed by an inner tubular housing member 32 and an outer tubular housing member 33. The lower end of the housing under the sleeve valve is partially open into the upper end of the outer leg of the chamber 7 formed between the tubular members 8 and 9. 35 is an annular pas-

5 sage formed between the perimeter of tube 3 and the inside diameter of the housing member 32. It connects the pressure gas supply passage 5 with perforations or ports 36, which in turn make communication between passage 35 and the housing space in which the sleeve valve operates, when the perforations 36 are uncovered by said valve. The total cross sectional area of perforations 36 and/or of passage 35, should preferably be restricted to the minimum actually required to pass, 10 with some wire-drawing, the quantity of pressure gas required for propelling the secondary plunger at the required velocity. The cross-sectional area of the opening 34 between the valve housing space and the chamber 7 should be ample and largely in excess of that of 35 or 36 so that practically all the wire-drawing will take place in 36 and/or 35 when the secondary plunger reaches the end of its up-stroke and releases the propelling gas from the eduction tube 3 under the plunger and from chamber 7. This release of gas permits springs 37 and 38 to close the gas admission valve 31 against reduced pressure in the housing space under it. 37 is a sleeve valve spring. It resists the opening of valve 31 from its closed position 20 as shown, to its initial opening position of perforations 36 and to the full open position of the valve. It acts to close said valve from its full open position to its full closed position against reduced pressure in chamber 7. 38 is another 30 sleeve valve spring which opposes the opening of said valve by pressure gas from the surface source from the initial opening position of perforations 36 to the full open position of the valve. This spring 38 also acts in concert with spring 37 to move valve 31, against reduced pressure under it, from its full open position to that position when it just closes perforations 36. From this position spring 37 alone completes the closing of the valve against a still further reduced pressure 40 in chamber 7 due to the continued release of plunger propelling gas from eduction tube 3. I have omitted the spring 37 from Figs. 2 and 5 for clarification purposes. 40 are pressure relief holes through the wall of housing member 33. 45 They make communication between the housing space above the sleeve valve and the casing space, to release any vagrant pressure above casing pressure, from the former into the latter. 41 is a cushioning recess into which the upper end 50 of the sleeve valve 31 enters as it approaches its top position to cushion the stopping of same.

The space between the housing 33 and the casing 1 may be sealed at 42 by a gas packer shown in Fig. 5 placed above the gas admission valve housing to separate the casing space into upper and lower compartments when the string of tubing 4 is omitted and the upper compartment used to convey pressure gas from the surface source to the gas admission valve through passage 35 and perforations 36.

43 is a casing head secured at the upper end of casing 1. 44 is a gas supply pipe through which a regulated supply of reduced pressure gas from a surface source is fed to the casing space to make up any deficiency in quantity of formation gas to operate the primary plunger lift; or to supply pressure gas to the gas admission valve 31 when string of tubing 4 is omitted. 45 is a gas discharge pipe connected with the field gas gathering system for discharging and conserving any excess of formation gas from the casing space not used or released by the plunger lifts. 46 is a gas supply pipe for furnishing regulated pressure gas from a surface source through pas- 75

sage 5 to the gas admission valve 31 housing space and chamber 7.

47 is a gate valve used for trapping such parts as plungers when their removal from the well is required. 48 is a buffer of resilient material for cushioning the secondary plunger should it come to the surface unloaded. 49 is a cap for closing the upper end of the secondary eduction tube 50. 51 is an outlet pipe closed normally by a valve 52.

10 A plunger-retaining latch 24 and its automatic control mechanism are secured upon the extension head 23. The latch bolt 24 is extended into an opening in the side of 23 and has a stem 53 projecting outwardly through the wall of the bracket 54 to connect at 55 to a bell-crank lever pivoted upon a support at 56. The outer arm of the lever engages the rod 57 upon a piston 58 movable within a cylinder 59 and held resiliently downward by a spring 60. The cylinder 59 has a port below the piston 58 to which is secured a pipe 61 which connects at its other end with a port 62 in the tube extension head 23. There is a check valve 63 in this line allowing passage of fluid from 23 to the cylinder. I provide a by-pass around the check valve 63 by way of a small pipe 64 in which is a hand adjusted choke valve 65 for regulating the time during which the secondary plunger is held in its upper position. Other suitable automatic means may be substituted for retaining the plunger in its upper position and releasing it. It will be understood that the latch 24 will be moved to plunger engaging position by the pressure through pipe 62 of fluid being forced upwardly by the plunger. When this pressure is later released, the spring will move piston 58 back downwardly to retract latch 24 and release the plunger. The time of release may be regulated by valve 65 in pipe 64 which controls the passage of fluid from beneath the piston 58.

40 The operation of the method and device is as follows:

The well has been shut down and is to be started up again. The secondary plunger 25 was 45 permanently latched in its highest operating position before the well was shut down and is in that position. Primary plunger 15 is in its low position on top of cushion stop 13 with its valve 14 shut. Liquid has risen in the casing space 50 12 and in primary eduction tube 2 and its surface level is at the "headed-up" or "standing-level" elevation.

55 Pressure gas from a surface source is admitted by hand into casing space 6 from pipe 44 and builds up gas pressure in the well bore and casing space 12 above the liquid in same and displaces liquid into the primary eduction tube 2 and moves primary plunger 15 to its highest position where plunger valve 14 is opened. Liquid passes on through valve 14 and discharge valve 17 into chamber 18 and on into the secondary eduction tube 3 and (chamber 7 being full) continues to rise in 3. The liquid level in the casing space 12 continues to be depressed in elevation until gas breaks through into the primary eduction tube 2 at its extreme bottom end and is noted at the surface. Pressure gas is then shut off by hand from the casing space 6 until pressure in same has lowered sufficiently to permit gas admission valve 31 to be opened by the pressure of the column of liquid in eduction tube 3.

70 Pressure gas from the surface source is then turned on by hand from pipe 46 into annular 75

passage 5 and gas admission valve 31 is thus opened full and the pressure gas passes on into the outer leg of chamber 7 and displaces the liquid from the outer and inner legs of same and raises it through chamber 18 up into the secondary eduction tube 3. As soon as pressure gas breaks through the liquid column in 3 to the surface the secondary plunger 25 is released by hand and falls to its low position underneath its load of liquid and plunger valve 26 shuts. Secondary plunger 25 then makes its up-stroke and as it approaches the end it discharges the liquid above it, propelled by pressure gas still admitted by valve 31. When the secondary plunger 25 reaches its top position in tube 3 and has discharged the fluid above it, latch 24 engages and holds it in that position. Propelling gas from 3 under the plunger and from discharge chamber 18 and from chamber 7 then escapes through perforations 21 into flow line 22 and gas pressure in them is reduced which automatically causes the gas admission valve 31 to close, discontinuing the inflow of pressure gas.

At this stage of the initial operation both the primary and secondary lifts have each completed 25 one discharge of liquid. The secondary lift is ready to receive regular cyclic discharges of liquid from the primary lift and lift them to the surface and discharge them and continue cyclic operations automatically. The primary lift 30 however, after making only one discharging cycle, is not ready to continue operating automatically because liquid and gas conditions in the well space 12 and adjacent producing formation have not yet stabilized in these respects: First, 35 the flow of formation gas into the well bore has not even approached what it will normally be under continuous operation and second; only a small part of the accumulation of liquid in the well from the shut-down period has been removed from space 12 and primary eduction tube 2 and the adjacent producing formation; and besides, the oil is more or less inert.

Before the conditions are stabilized and the well is in shape for continued automatic operation of the complete lift, it may therefore be necessary to repeat several times the initial cycles largely by hand control, until it is ready for automatic control operation, which will then be as follows:

50 Secondary plunger 25 is being held at the top by the latch 24. Gas has been discharged and gas pressure released and practically all liquid has been removed from the entire secondary lift and from the chamber 7 of the primary lift. The gas admission valve 31 has closed and as 55 pressure has been removed from above it the primary discharge valve 17 opens and releases gas from the primary eduction tube 2 above the slug of liquid on top of the primary plunger 15. This gas escapes through valve seat 16, valve 17, 60 chamber 18, eduction tube 3, perforations 21 and flow line 22.

Formation gas and/or pressure gas has built-up pressure in casing space 12 and has depressed 65 the liquid level in same until it uncovered the extreme lower end of eduction tube 2, and thus permits gas from space 12 and the adjacent producing formation to enter eduction tube 2 under the primary plunger 15 and drop and displace 70 liquid therefrom. The primary plunger then resumes its upward stroke and first displaces the superimposed free gas and then discharges the liquid slug through primary discharge seat and valve 16 and 17 into chamber 18. The superim- 75

posed gas passes out through eduction tube 3 and perforations 21 and flow lines 22. The liquid spills over into the inner leg and through perforations 11 into the outer leg of chamber 7. The propelling gas under plunger 15 in the primary eduction tube 2 passes on through plunger valve 14, discharge seat and valve 16 and 17, discharge chamber 18, into eduction tube 3 and out of the well through perforations 21 and flow line 22. This reduces gas pressure in eduction tube 2 under the primary plunger 15 and causes fluid to flow into same from space 12 to the predetermined plunger liquid-loading elevation in same. Said plunger then falls with its valve 14 open and passing into the loading liquid contacts with cushion stop 13 which closes 14 and brings the plunger to rest. These primary lift round-trips of the plunger 15 are consecutively repeated, with the secondary lift plunger held at the top, until chambers 7 and 18 are fully charged with liquid and the lower portion of eduction tube 3 is also charged up to the predetermined elevation, at which the gas admission valve 31 is actuated, initially uncovering perforations 36 and admitting pressure gas 5 from passages 5 and 35 to the housing space under the valve 31. This opens it to the full open position and admits pressure gas to the outer leg of chamber 7 on top of the liquid in same, displacing the liquid in this leg and the liquid in the inner leg of chamber 7 and transferring it into the lower portion of the secondary eduction tube 3 to the plunger liquid-loading elevation in same. The secondary plunger has been automatically unlatched and falls through the liquid and comes to rest on cushion stop 27 which closes its valve 26 and said plunger then makes its up-stroke, propelled by pressure gas still fed past the gas admission valve 31. As this secondary plunger rises on its up-stroke it lifts intact the superimposed slug of liquid; the stratum of free gas above the liquid slug being displaced through perforations 21 and flow line 22 as the plunger rises, until the top of the liquid slug reaches the perforations 21 when the discharge of liquid from eduction tube 3 begins. It continues until said secondary plunger reaches the end of its stroke and completes the liquid-discharging minor portion of its up-stroke. The latch 24 then engages said plunger and the propelling gas from the eduction tube 3 under the plunger escapes through perforations 21 and flow line 22. The reduced pressure resulting, in eduction tube 3 and in chamber 7 and in the housing space under the gas admission valve 31, permits valve springs 37 and 38 to close the valve 31. Pressure is then exhausted from eduction tube 3 and chambers 7 and 18 and the primary lift resumes its automatic operation. The cycles are continuously repeated.

60 What I claim as new is:

1. A plunger lift device including an eduction tube, a primary stage therein, a freely moving plunger in said primary stage, a standing valve at the upper end of said primary stage, an intermediate stage liquid reservoir in or around the upper portion of said primary stage below said standing valve, an upper secondary stage in said eduction tube, a second freely moving plunger above said standing valve in said secondary stage, there being openings into said tube below said second plunger, a sleeve valve closing said openings, means to conduct gas or air under pressure from the surface to said valve, said valve opening in response to the head of liquid in said eduction tube above said standing valve.

2. A plunger lift apparatus including a tubing, a tubular valve housing thereon comprising two spaced pipes including an annular valve chamber between them, the inner wall of said chamber being formed with perforations adjacent its lower end, a sleeve valve controlling said openings and closing the lower end of said chamber, means to hold said valve resiliently downwardly into closed position, a fluid receiving chamber below said valve chamber, a primary eduction tube spaced inwardly from said chamber and extending below the same, the space between said eduction tube and said fluid receiving chamber being connected to said chamber by openings at the lower end of said chamber, a freely moving plunger in said primary eduction tube, a stop for said plunger at the upper end of said primary eduction tube, a standing valve above said stop, a second eduction tube above said standing valve, a plunger freely movable therein, and means to introduce gas under pressure past said sleeve valve to said second eduction tube below said second plunger responsive to the head of liquid in said second eduction tube.

3. A plunger lift apparatus including a tubing, 25 a tubular valve housing thereon comprising two spaced pipes including an annular valve chamber between them, the inner wall of said chamber being formed with perforations adjacent its lower end, a sleeve valve controlling said openings and closing the lower end of said chamber, means to hold said valve resiliently downwardly into closed position, a fluid receiving chamber below said valve chamber, a primary eduction tube spaced inwardly from said chamber and extending below the same, the space between said eduction tube and said fluid receiving chamber being connected to said chamber by openings at the lower end of said chamber, a freely moving plunger in said primary eduction tube, a stop for said plunger at the upper end of said primary eduction tube, means to prevent the entrance of fluid from above to said primary eduction tube whereby liquid may be accumulated in said fluid receiving chamber and about said eduction tube by a plurality of consecutive stroke cycles of the primary plunger, a second eduction tube above said primary eduction tube, a freely movable plunger therein, means to discharge pressure gas into said second eduction tube past said sleeve valve 50 when the head of liquid in the same from the primary lift has reached a predetermined amount, said sleeve valve being closed when said second plunger has been raised to the surface and said pressure reduced.

4. In a plunger lift device, a secondary eduction tube, a primary eduction tube extending from the liquid in the well upwardly into said secondary eduction tube and connected with the lower end of said secondary eduction tube, a plunger freely movable in said primary tube, a standing valve at the upper end of said primary tube, a second plunger in said secondary tube above said standing valve, a stop for said second plunger on said valve, an annular passage 65 about said secondary eduction tube for pressure gas or air from the surface, a valve in said passage controlling the entrance of gas therefrom to said tube, said valve being opened in response to the liquid pressure in said secondary eduction tube.

5. In a plunger lift well-pumping apparatus, an eduction tube, a primary stage therein, an intermediate stage liquid reservoir in or around the upper end of said primary stage, a secondary stage, a valve 75

controlling admission of fluid from said primary to said secondary stage, a freely moving plunger in each of said stages, the secondary stage plunger lifting superimposed in one stroke-cycle substantially the same quantity of liquid lifted by the plural consecutive stroke-cycles of the primary plunger, means to introduce gaseous fluid under pressure below said primary plunger to lift the same, and separate means automatically responsive to fluid pressure exerted thereon to introduce below said secondary plunger pressure gas or air from a surface source.

6. A plunger lift device including two stages, a lower lift shorter stroke primary stage, an interstage liquid reservoir in or around the upper

end thereof, and a higher lift larger stroke secondary stage extending from near the upper end of the primary stage to the surface of the ground, a freely moving plunger in each of said stages, means to exert gaseous fluid pressure below said primary stage plunger and lift the liquid from near the pumping depth into said interstage reservoir and the lower end of the secondary stage, means to introduce below said secondary stage plunger gaseous pressure fluid from a surface source, and a fluid pressure responsive valve controlling the admission of gaseous fluid to said secondary stage.

CLARENCE N. SCOTT.
